HOBBYHORSE HEAD

Eugene Porozynski, Cleveland Heights, Ohio

Application April 12, 1950, Serial No. 9,157

Term of patent 14 years

(Cl. D34—15)

To all whom it may concern:

Be it known that I, Eugene Porozynski, a citizen of the United States, residing in the city of Cleveland Heights, county of Cuyahoga, and State of Ohio, have invented a new, original, and ornamental Design for a Hobbyhorse Head, of which the following is a specification, reference being had to the accompanying drawing, forming a part hereof.

Figure 3 is a side elevation of the hobbyhorse head, both sides of the head being identical in appearance.

I claim:

The ornamental design for a hobbyhorse head, as shown and described.

EUGENE POROZYNSKI.
